Primary Examiner—Alan P. Douglas*Assistant Examiner*—Monica A. Hannon*Attorney, Agent, or Firm*—Pennie & Edmonds**[57]****CLAIM**

The ornamental design for a bottomrail endcap for venetian blinds, as shown and described.

DESCRIPTION

FIG. 1 is a front perspective view of a bottomrail endcap for venetian blinds showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof; and,

FIG. 7 is a cross-sectional view taken along the line 7—7 of FIG. 6 thereof.

FIG. 1

FIG. 2

FIG. 3

FIG. 4

FIG. 5

FIG. 6

FIG. 7
